CLOCK DIAL

Roman J. Szalek, La Salle, Ill., assignor to General
Time Corporation, Thomaston, Conn.

Filed Dec. 18, 1974, Ser. No. 534,061

Term of patent 14 years

Int. Cl. D10—07

U.S. Cl. D10—126

The figure is a front elevational view of a clock dial showing my new design. The clock dial is conventionally of no appreciable thickness with the pattern within the dash-line segment being understood to be continuous throughout the entire dial.

I claim:

The ornamental design for a clock dial, substantially as shown and described.
